GASEOUS-DISCHARGE DEVICE

Paul W. Stutsman, Needham, Mass., assignor to
 Raytheon Manufacturing Company, Newton,
 Mass., a corporation of Delaware

Application June 16, 1950, Serial No. 168,426

2 Claims. (Cl. 313—185)

1

This invention relates to gaseous-discharge devices, and more particularly to discharge devices which may be used as voltage regulators. In the construction of voltage regulator tubes of the sub-miniature type, several problems are encountered.

Because of the small size, it is difficult to produce a device which will carry relatively large currents, for example, up to twenty-five milliamperes. It has been discovered that, by utilizing the device wherein the cathode surrounds the anode, a large cathode area is exposed such that a relatively wide range of currents may be drawn from the cathode surface without appreciably changing the cathode fall potential thereof.

In previous sub-miniature discharge devices, it was found that when a sub-miniature bulb was used insufficient quantities of the gaseous medium were available to produce a long life of the discharge device, since the gas became occluded in the metallic elements of the device thereby lowering the pressure to a point where stable operation was no longer possible.

This invention discloses a structure and gaseous filling whereby a relatively high pressure may be used, thereby providing a sufficient reserve of a gaseous medium so that the discharge device may be operated for a long period of time, for example, in excess of five thousand hours, without seriously decreasing the supply of the gaseous medium.

Briefly, this is accomplished by using a gaseous mixture comprising approximately forty per cent argon and sixty per cent neon. It has been found that this mixture causes considerably less sputtering of the cathode surface than may be had with either pure argon or pure neon.

In addition, this invention discloses a cathode support member which effectively shields the cathode surface in such a way that the discharge is confined to the desired area between the cathode and the anode, thereby eliminating sputtering and condensation of cathode material on insulating supports which would eventually produce a short circuit, and eliminating variations of the voltage drop of the discharge due to variations in the position of the discharge path which would be encountered in the absence of the shielding support member.

In addition, this invention discloses the substantial elimination of the positive column drop normally encountered in the discharge. This is accomplished by placing the anode substantially at the minimum breakdown distance from the cathode. This will place the anode in or ad-

2

acent the Faraday dark region of the discharge, and, for the particular electrode configuration and gaseous medium disclosed herein, the position of the anode is substantially at the junction of the Faraday dark space and the positive column. Since the positive column drop has a negative voltage current characteristic which might produce oscillations in the circuit being regulated, substantially eliminating the positive column drop produces a nonoscillatory circuit. Any portion of the positive column drop which still remains will have its negative characteristic more than compensated for by the slight positive voltage characteristic of the remaining glow discharge phenomena.

Other and further advantages of this invention will be apparent as the description thereof progresses, reference being had to the accompanying drawing, wherein:

20 Fig. 1 illustrates a longitudinal, cross-sectional view of a gaseous-discharge device embodying this invention;

Fig. 2 illustrates a transverse, cross-sectional view of the discharge device shown in Fig. 1 taken along line 2—2 of Fig. 1; and

Fig. 3 illustrates a graph demonstrating the characteristics of various mixtures of argon and neon.

Referring now to Figs. 1 and 2, there is shown 30 a sub-miniature envelope 10 which may be, for example, of glass. Extending upwardly from the bottom of envelope 10 through a glass press 11 are three leads 12, 13 and 14, respectively. Lead 13, which is the center lead, is connected to an 35 anode support rod 15 which is coaxial with envelope 10. Attached to anode support rod 15 are two anode support cups 16, said cups surrounding anode rod 15 and being rigidly secured thereto by any desired means such as by a friction fit or by welding.

Extending over a portion of anode rod 15 and both support cups is an anode cylinder 17 which is coaxial with anode support rod 15, said anode cylinder 17 being rigidly attached to support 45 cups 16, as by welding. Each of cups 16 has a small hole 18 in the bottom thereof which allows gases to pass freely in and out of anode cylinder 17.

Surrounding anode cylinder 17, spaced therefrom and coaxial therewith is a cathode cylinder 19 which may be made, for example, of molybdenum. Anode cylinder 17 is somewhat longer than cathode 19 and extends out of cathode cylinder 19 beyond both ends thereof. Closely 55 surrounding cathode 19 and attached thereto, as

by welding, is a nickel cathode support cylinder 20 which is substantially the same length as anode cylinder 17 and consequently extends out of the ends of cathode cylinder 19.

Support cylinder 20 is rigidly attached, as by welding, to a pair of side support rods 21 and 22 whose lower ends are attached to leads 12 and 14, respectively. Both anode support rod 15 and side support rods 21 and 22 are somewhat longer than anode cylinder 17 and cathode support 20 and consequently extend out beyond the ends thereof.

A pair of mica spacers 23 and 24 is placed over the lower ends of side support rods 21 and 22 and anode support rod 15, thereby rigidly maintaining the correct spacing between the lower end of anode 17 and cathode 19. Similarly, another pair of mica spacers 25 and 26 is positioned over the upper ends of side rods 21 and 22 and anode support rod 15 to maintain the correct spacing therebetween. Axial movement of spacers 23, 24, 25 and 26 on side rods 21 and 22 is prevented by a plurality of metallic tabs 27 welded to side rods 21 and 22. Similarly, longitudinal movement of anode support rod 15 relative to spacers 23, 24, 25 and 26 is prevented by a metallic tab 28 welded to anode support rod 15 at a point just above upper mica spacer 26 and by a metallic tab 29 welded to anode support rod 15 just below lower mica spacer 24. Thus, both axial and transverse movement of the anode structure relative to the cathode structure is prevented.

Mica spacers 23, 24, 25 and 26 extend outwardly and engage the walls of envelope 19, thereby preventing movement of the tube elements within the envelope.

Attached to the upper end of anode support rod 15 is a getter structure which may be of any well-known type, for example, a U-shaped metallic member 30, across which is connected a bar of getter material which is flashed by induction heating.

Since molybdenum cathode cylinder 19 is surrounded by the support cylinder 20, the discharge is confined to the inner surface area of the molybdenum cathode cylinder 19 with possibly a small amount extending over the ends of the molybdenum cylinder 19. However, the discharge cannot move around to the outside of cathode cylinder 19 as would be possible in the absence of the supporting shield member 20, and hence changes in the voltage drop between the cathode and anode during the discharge, and due to changes in the length of the discharge path, are substantially eliminated. Moreover, with the spacing between the molybdenum cathode 19 and the anode as shown, the anode is positioned substantially at the minimum breakdown distance from the cathode, thus substantially eliminating the positive column drop with its associated negative voltage current characteristic from the discharge.

Referring now to Fig. 3, there is shown a graph illustrating the voltage drop across a discharge using various percentages of argon and neon. Along the axis of ordinates is plotted the voltage drop in volts, and along the axis of abscissas is plotted the percentage of argon, with the remainder of the mixture being made up of neon, the particular curve being taken for a gaseous pressure on the order of five centimeters of mercury.

At a zero percentage of argon, which corresponds to a mixture of pure neon, a voltage drop of approximately one hundred and six volts is encountered, as shown by point 31 on the graph. When one per cent of argon is added, the voltage drops to approximately eighty-five volts, as shown

by point 32 on the graph, this voltage being the lowest drop which is encountered for a gaseous mixture of argon and neon at this pressure. This particular mixture of one per cent argon and ninety-nine per cent neon is well known and used in many discharge devices. However, if it is desired to construct a tube having a voltage drop of substantially one hundred volts, a mixture of one per cent argon and ninety-nine per cent neon at a pressure of five centimeters of mercury produces a drop which is too low. While the potential drop for this mixture could be raised by decreasing the pressure, this results in an insufficient quantity of gas within the envelope to produce a long-life tube.

Similarly, if either a mixture of one hundred per cent argon or one hundred per cent neon were used, and the pressure raised to thereby lower the voltage drop of the discharge, sputtering of the cathode surface is so intense that a short may be quickly produced, for example, within one hundred hours of operation. This sputtering occurs by reason of concentration of the area of emission of electrons to a particular spot on the cathode surface, and results in stalactite formations which extend outwardly from the anode surface until they reach the cathode and short the device.

It has been discovered that a large range of voltage values may be had for a given pressure by varying the percentage of argon in the neon mixture. For example, when the mixture comprises forty per cent argon and sixty per cent neon at a pressure of five centimeters of mercury, a voltage drop of substantially one hundred volts occurs across the discharge. When the gases are mixed, the emission area on the cathode spreads out over an extended area, and hence there is very little sputtering in the cathode surface, and there is no concentration of sputtering of the type which would build up shorting stalactites.

Furthermore, since the shape of the curve as it passes through the mixture of forty per cent argon at one hundred volts, as shown by point 33 on the graph, is relatively flat, hence production tolerances of the gaseous mixture and pressure need not be held to extremely high accuracies in order to result in a large number of tubes which have substantially the same voltage regulating properties.

This completes the description of the invention illustrated herein. However, many modifications thereof will be apparent to persons skilled in the art without departing from the spirit and scope of this invention. For example, other materials could be used for the cathode and cathode support cylinder instead of molybdenum and nickel. Other support structures could be used, and other mixtures of the gaseous medium could be used to produce different regulating voltages in accordance with the teaching of the graph of Fig. 3. Therefore, it is desired that this invention be not limited to the particular details of the species of the invention illustrated herein, except as defined by the appended claims.

What is claimed is:

1. A gaseous discharge device comprising an envelope having therein a hollow cylindrical anode, an anode support rod extending through said anode spaced therefrom, a molybdenum cathode spaced from said anode by a distance substantially equal to the distance from the cathode to the outer edge of the Faraday dark region whereby the positive column drop of the gaseous

discharge is substantially eliminated, a nickel cathode support member surrounding said cathode and coaxial therewith, said cathode support member and said anode extending axially beyond both ends of said cathode member, and a gaseous filling comprising substantially three parts of neon to two parts of argon at a pressure on the order of five centimeters of mercury.

2. A gaseous discharge device comprising an envelope having therein a hollow cylindrical anode, an anode support rod extending through said anode spaced therefrom, a molybdenum cathode spaced from said anode by a distance substantially equal to the distance from the cathode to the outer edge of the Faraday dark region whereby the positive column drop of the gaseous discharge is substantially eliminated, said distance also being substantially equal to the minimum breakdown distance, a nickel cathode support member surrounding said cathode and co-

axial therewith, said cathode support member and said anode extending axially beyond both ends of said cathode member, and a gaseous filling comprising substantially three parts of neon to two parts of argon at a pressure on the order of five centimeters of mercury.

PAUL W. STUTSMAN.
